UNITED STATES PATENT OFFICE.

CARL KOCH, OF LINDEN-ON-THE-RUHR, GERMANY.

LAMP-IGNITION DEVICE.

1,015,193.

Specification of Letters Patent.

Patented Jan. 16, 1912.

Application filed August 30, 1909. Serial No. 515,295.

To all whom it may concern:

Be it known that I, CARL KOCH, a subject of the Emperor of Germany, and residing at Linden-on-the-Ruhr, Germany, have invented certain new and useful Improvements in Lamp-Ignition Devices, of which the following is a specification.

In the case of miners' lamps, the lighting of which is effected by pyrophorous metal, the non-burned particles which are rubbed off when lighting the lamp, and remain in the interior of the lamp body, form a considerable danger in case of fire damp as when the lamp gets hot, they ignite when the lamp falls down or is shaken, and when they fall through the wire cage, they can bring about an explosion of the fire-damp. In order to reduce this danger as much as possible, it is necessary to give the spark emitting alloys used for lighting such lamps, as high a point of ignition as possible. But then again it is necessary that the friction for the ignition should be a very energetic one in order to insure getting a spark from such alloys and to avoid shavings being rubbed off without effecting ignition.

Well known ignition or lighting devices have the drawback that the movement of the rubber depends on the speed with which the ignition device is operated. According to the present invention the movement of the rubber takes place independently of the hand movement by means of an intermediary portion the limit of travel of the rubber and its velocity always remaining the same.

In the accompanying drawings:—Figure 1 is a sectional elevation of a spring operated lighting device. Fig. 2 is a sectional view taken at a right angle to the view in Fig. 1. Fig. 3 is a sectional plan of the same device.

In the device illustrated the single portions of the ignition device are mounted on a disk inserted in the casing of the lamp. The spindle which is provided with a slot for operating it, passes through the casing and can be rotated in the known manner by a wheel or sheave passing through the top

of the lamp. The pyrophorous alloy is arranged in the tube *a* and is pressed in the known manner by a spring *f* against the rubber *c*. The rubber *c* is laterally adjustable, it is held in its position by the spring *55* and is provided with a projection *d*. To the spindle is secured a nut *e* which, on the spindle rotating engages with the projection of the rubber, moves the latter laterally and places the spring *f* in tension and during the *60* subsequent turning, slides off from the projection and again releases the rubber. Owing to the action of the spring, the rubber is brought back into its original position and rubs off little shavings from the pyrophorous metal, which, owing to the quickness with which this movement is carried out, are ignited in a reliable manner. In order to enable the longest possible piece *65* of pyrophorous metal to be put in, the tube *70* is preferably mounted in the cover obliquely and is situated with its longer portion under the cover in the casing. The rubber is preferably made of dove-tailed shape at the *75* holder and can be easily replaced by loosening the screw. In order to direct the sparks to the wick, it is preferable to make the teeth of the rubber obliquely, namely so that the vertical line of the burner forms *80* with the teeth a pointed angle converging at the bottom.

As pyrophoric substances can be used pyrophoric alloys, containing cerium alloyed with iron or such pyrophoric alloys which consist of magnesium, aluminium, and like *85* metals alloyed with the so-called "rare earth metals," especially with a mixture containing cerium, lanthanum and didymium metal.

What I claim as my invention and desire to secure by Letters Patent is:—

An ignition device for miners' safety lamps, comprising, in combination, means for supporting a pyrophoric substance in operative position, a reciprocatory slide having a friction surface arranged to co-operate with said pyrophoric substance, a leaf spring lying in the plane of movement of said slide and acting thereon to move the latter in one direction, and a disk mounted revolvably beneath the plane of said slide *95* *100*

and spring and having means for gradually
retracting the slide against the action of
the spring and for suddenly releasing the
slide to permit a quick motion of the slide
5 under the action of the spring, the parts
being in flat compact form to enable the de-
vice to be placed in a flat box.

In testimony whereof I have signed my
name to this specification in the presence
of two subscribing witnesses.

CARL KOCH.
